UNITED STATES PATENT OFFICE.

EDWIN E. THOMAS, OF PORTLAND, OREGON.

LIFTING-JACK.

No. 829,238.

Specification of Letters Patent.

Patented Aug. 21, 1906.

Application filed March 12, 1906. Serial No. 305,481.

To all whom it may concern:

Be it known that I, EDWIN E. THOMAS, of Portland, county of Multnomah, Oregon, have invented certain new and useful Improvements in Lifting-Jacks, of which the following is a specification.

Lifting-jacks as usually made must be placed close to the load to be raised, and oftentimes the lifting operation is attended with great danger to the life and limb of the operator, particularly when the load is high and composed of lumber or of loose material. It has been found also very difficult to get down low enough to use an ordinary jack when the load is close to the ground. When the load is wide or on a platform, the jack is located under the middle of it with a suitable cross-bar; but it is a difficult and dangerous operation to place the jack in that position. Sometimes two jacks are used, one on each side of the load and connected with one another by a cross bar or beam. This, however, has been found to be a laborious and tedious method of lifting a load.

The object, therefore, of my invention is to provide a lifting-jack capable of use under various conditions and of very simple construction, having but few working parts and these being plainly exposed to view to facilitate their adjustment and permit convenient inspection and repair.

A further object is to provide a lifting-jack which will enable the operator to stand at a safe distance from the load during the operation of raising it.

A further object is to provide a jack which can be easily and quickly lowered without danger of injuring the attendant.

Other objects of the invention will appear from the following detailed description.

The invention consists, generally, in a base or bar normally stationary and a movable bar having pivotal connections with the base and held in parallel relation therewith, said movable bar engaging the bottom of the load to be raised.

Further, the invention consists in providing the movable bar with a hook or step device whereby the preliminary raising of a low-down load may be effected.

Further, the invention consists in various constructions and combinations, all as herein-after described, and particularly pointed out in the claims.

In the accompanying drawings, forming part of this specification, Figure 1 is a side elevation of a lifting-jack embodying my invention, the movable bar being shown in its down position. Fig. 2 is a similar view illustrating the jack in its raised position. Fig. 3 is a top view of the jack. Fig. 4 is a sectional view on the line *xx* of Fig. 2. Fig. 5 is a sectional view on the line *zz* of Fig. 2. Fig. 6 is a sectional view on the line *yy* of Fig. 2. Fig. 7 is a detail view of the mechanism for operating the jack.

In the drawings, 2 represents a base rail or bar having forward and rear trucks 3 and 4 pivoted thereon on each side of the bar. These trucks or wheels are of any suitable size and facilitate the movement of the jack from place to place. In place of the trucks shoes may be provided, or the rail may be allowed to rest directly upon and slide on the ground.

5 is a bar arranged above the bar 2.

6 is a lever pivoted at its upper end to the bar 5 near one end, and having an antifriction-roller 7 at its lower end, which rolls on the edge of the bar 2, the lever 6 being composed, preferably, of two parts or pieces, the ends of which lap the upper edge of the bar 2 and form guides for the wheel or roller thereon. A second lever 8 is pivoted at its lower end to the bar 2 beneath the pivot of the other lever on the bar 5, and the upper end of the lever 8 has an antifriction roller or wheel 9, which engages the lower edge of the bar 5, being guided thereon by the projecting forked end of the lever 8. The levers 6 and 8 are connected with one another centrally by a pivot-pin 10. The bars 2 and 5 are thus held in parallel relation with one another during the upward and downward movement of the jack.

The end of the bar 5 is provided with a pivoted hook or step 11, which extends down below the level of the base-rail of the jack and is adapted to be slipped in under a timber or load which lies near the ground to enable the operator to impart a preliminary raising movement to the load preparatory to slipping the bar 5 beneath the same, the load of course being blocked up to allow the jack to be lowered and the bar 5 inserted beneath the load. In some instances the movement of the hook may be sufficient to raise the load to the desired height without utilizing the bar. The

hook, however, is intended as an adjunct to the bar and may be used in connection with it or not, as preferred. Its attachment to the jack gives it a wider range of use than usually found in appliances of this kind.

On the rear end of the base-rail 2 a bar 12 is pivoted, having a series of ratchet-teeth 13, said bar projecting at its upper end through a slot 14, provided in a head-block 15 on the bar 5, the ratchet-bar serving as a guide for the head-block in its vertical movement with the bar 5. An operating-lever 16 is pivoted at 17 on the block 15 and carries a gravity-dog 18, pivoted at 19 thereon and having a weighted handle 20, which normally holds the dog in engagement with the ratchet-teeth 13. A gravity-dog 21 is pivoted on the bar 5 and has a weighted handle 22, which holds the said dog in engagement with the ratchet-teeth 13. Both of these dogs are adapted to slip over the ratchet-teeth when the bar 5 is raised and lock the said bar against downward movement. The lever 16 when raised on its pivot will move the dog 18 over one or more ratchet-teeth, according to the degree of movement of the lever, and then when pressure is applied to the outer end of the lever to force it down the bar 5, whereon the short arm of the lever is mounted, will be lifted to raise the load. During the time the lever 16 is being swung upward the dog 21 will remain in engagement with the ratchet-teeth and lock the bar 5 against depression. In other words, the dog 18 will act as a fulcrum for the lever 16 during the raising of the bar 5, while the dog 21 will serve as a lock and relieve the lever 16 of the weight of the load and allow it to be oscillated easily to impart the upward step-by-step movement to the lifting-bar 5. The load may be anywhere along the horizontal top of the bar 5. The levers 6 and 8 will evenly distribute the strain, and it will be immaterial whether the load be upon the end of the lifting-bar or the middle portion thereof. The locking-dog 21 will slide over the ratchet-teeth as the bar 5 is raised tooth by tooth, and there will be no danger of the load falling through accidental movement of the operating-lever.

When it is desired to lower the load, the operator will grasp the lever 16 with one hand and raise the weighted handle 20 with the other hand, thus disengaging the dog 18 from the ratchet-teeth. This will allow the lever to be dropped and the dog 18 to engage a lower tooth on the rack-bar. Then bear down on the lever 16 until the load has been raised slightly and raise the handle 22, disengaging the dog 21 from the ratchet. Then by allowing the weight of the load to swing the lever 16 upward the dog 21 may be lowered one or two teeth, as desired. By repeating the above-described operation the jack with the load thereon can be easily and

quickly lowered to the desired level. If for any reason it is desired to drop the jack instantly to its lowest position, the lever 16 is raised to a point above the upper limit of its normal stroke or until a beveled surface 23 on the said lever engages a pin 24 on the block 15. When this occurs, the dog 18 will be automatically disengaged from the ratchet-teeth, and upon lifting the handle 22 the dog 21 will also be disengaged and the jack will drop by gravity to its depressed position. When it is desired to raise the jack to its elevated position without any load thereon, the operator will grasp the handle 16 near its pivot, and an upward pull thereon will lift the bar 5 and its connections to the desired level.

In Fig. 1 I have shown the jack in its down position, with the pivoted hook inserted under a timber which is too low to allow the bar 5 to be thrust beneath it. By operating the lever 16 the person in charge of the jack can raise the timber until it is above the position of the bar 5 shown in Fig. 1 and then when the timber is blocked the hook may be removed and the entire jack thrust under the timber, as also indicated in said figure, the dotted lines representing a stick of timber when first engaged by the lifting-hook, and then the same stick of timber raised to a sufficient level to allow the bar 5 to be thrust beneath it. I regard this lifting-hook as a useful adjunct to my invention, but not an indispensable one, as the jack will be thoroughly practicable and a valuable device for handling lumber and other material, even if the hook is entirely omitted. I do not wish to be confined either to the use of the wheels or trucks in connection with this jack, as they may be omitted, if desired. In various ways also the details of the operating mechanism may be modified without departing from my invention.

I claim as my invention—

1. The combination with a base-bar, of a lifting-bar, means connecting said base-bar and said lifting-bar, means for raising and lowering said lifting-bar, and comprising a ratchet-bar and lever and dogs carried by said lifting-bar and lever and means carried by said lifting-bar and adapted to engage the bottom of a load below the level of said lifting-bar when in its depressed position, substantially as described.

2. The combination with a base-bar, of a vertically - movable lifting - bar supported thereon, said lifting-bar being horizontal and moving vertically in parallel relation with said base-bar, and a ratchet-and-lever mechanism for raising and lowering said lifting-bar and means for tripping said mechanism to allow the quick depression of said lifting-bar.

3. The combination with a base-bar having carrying-wheels, of a lifting-bar, means connecting said base-bar with said lifting-bar

and whereby their parallel relation is maintained, and means for operating said lifting-bar, said operating means comprising a ratchet-bar and lever and dogs carried by 5 said lifting-bar and lever.

4. The combination with a base-bar, of a vertically - movable lifting - bar, levers centrally pivoted to one another, each lever being pivoted at one end to one of said bars and 10 having an antifriction - roller at the other end adapted to travel on the edge of the other bar, and a ratchet-and-lever mechanism for raising and lowering said lifting-bar.

5. The combination with a base-bar, of a 15 vertically-moving lifting-bars supported thereon, a ratchet-bar mounted on said base-bar, a dog provided on said lifting-bar and engaging the teeth of said ratchet, an operating-lever pivoted on said lifting-bar, and a dog carried 20 by said operating-lever and also engaging the teeth of said ratchet, and said dogs normally locking said lifting-bar against depression, substantially as described.

6. The combination with a base-bar, of a 25 vertically-moving lifting-bars supported thereon, a ratchet-bar pivoted on said base-bar and whereon said lifting-bar is vertically 30 slideable, an operating-lever pivoted on said lifting-bar, a dog carried by said operating-lever and engaging said ratchet-teeth, said dog having a beveled surface adapted to engage a fixed pin provided on said lifting-bar when said lever is raised beyond the normal 35 limit of its upward movement, and a locking-dog carried by said lifting-bar and engaging

the teeth of said ratchet, substantially as described.

7. The combination, with a base-bar, of a vertically - movable lifting - bar supported thereon, said lifting-bar being horizontal and 40 moving vertically in parallel relations with said base-bar and a ratchet-and-lever mechanism having lifting and locking dogs and means for tripping said lifting-dog, whereby upon disengaging said locking-dog with one 45 hand and raising said lever with the other, said lifting-bar can be easily and quickly lowered, substantially as described.

8. The combination, with a base-bar, of a vertically-moving lifting-bar supported there- 50 on, a ratchet-bar pivoted on said base-bar and whereon said lifting-bar is vertically 55 slideable, an operating-lever pivoted on said lifting-bar, a dog carried by said operating-lever and engaging said ratchet-teeth, a locking-dog carried by said lifting-bar and also engaging the teeth of said ratchet, and means for automatically tripping said lever-dog when said lever is near the limit of its upward movement whereby upon raising said 60 lever slightly and tripping said locking-dog, said lifting-bar can be easily and quickly lowered, substantially as described.

In witness whereof I have hereunto set my hand this 20th day of February, 1906.

EDWIN E. THOMAS.
